(57) **CLAIM**

We claim the ornamental design for a duck blind cover, as shown and described.

DESCRIPTION

FIG. 1 is a perspective view of the duck blind cover;

FIG. 2 is a top plan view thereof;

FIG. 3 is a left side elevational view thereof, the right side being a mirror image thereof;

FIG. 4 is a front elevational view;

FIG. 5 is a back elevational view thereof; and,

FIG. 6 is a bottom plan view thereof.

The broken lines on the drawing are for illustrative purposes only and form no part of the claimed design.
